REGENERATIVE RADIORECEIVER

Walter Van B. Roberts, Princeton, N. J., assignor
to Radio Corporation of America, a corpora-
tion of Delaware

Application November 22, 1930
Serial No. 497,368

3 Claims. (Cl. 250—20)

My present invention relates to radio receivers, and more particularly to a portable, or mobile, radio receiver utilizing a novel method of cascade regeneration.

- 5 In addition to being economical in its consumption of power, a portable radio receiver should possess as great a degree of selectivity and sensitivity as is possible without impairing too greatly its fidelity. To secure these characteristics, it has been customary in the prior art to employ regenerative circuits in portable receivers. However, the use of regenerative circuits is attendant with various disadvantages tending to discourage the wide use of portable receivers.
- 10 15 One of the important disadvantages depends upon the fact that a single regenerative stage does not give sufficient amplification without critical tuning and regenerative adjustment, and without great loss of fidelity.
- 20 25 30 In such cases, one or more, non-regenerative stages connected in cascade ahead of the regenerative stage are usually employed. If, however, a plurality of regenerative stages is employed in cascade, the selectivity curve, is least sharp (fidelity best) when sufficient regeneration is used in the various tuned circuits to make their apparent tuning factors or coil efficiencies about equal, rather than to get the desired amplification all in one regeneration. That it to say, it has been found that better results are secured, from the point of view of selectivity and fidelity, when a plurality of tuned radio stages are connected in cascade, each including means for regenerating its tuned input circuit, 35 40 45 50 55 60 65 70 75 80 85 90 95 100 105 110

Now, I have found that two non-critical regenerations give more sensitivity and are easier to adjust than a single critical regeneration, provided a tube with good screening is utilized between cascaded tuned circuits, so that the tuned circuits are thoroughly shielded from each other. Thus, the total regenerative effect is truly cascaded; that is to say, the product of the two separate effects. Further, I have discovered that portable receivers can be made much more efficient than those constructed in the prior art by utilizing in addition to the aforementioned arrangement, a means for separately regenerating the tuned input circuit of the first of the stages of a plurality of tuned radio stages connected in cascade, the succeeding stage employing the usual reactive coupling between output and input circuits for regeneration. In this way, 55 it is possible to procure independency between the

regeneration and amplification in the receiver; a result not possible in the prior art.

Accordingly, it is one of the main objects of my present invention to provide a radio receiver, especially adapted for portable use, wherein there is employed a screen grid amplifier tube feeding a radio frequency system containing regenerative arrangements, the screen grid tube being fed by a resonant collecting circuit also containing a regenerative arrangement, the first mentioned radio frequency system being shielded from the second radio frequency system, and the regeneration of the collecting circuit being obtained by the use of a tube which is provided for that purpose exclusively.

Another important object of the invention is to provide in a radio receiver an arrangement whereby two successive tuned circuits are coupled by a space discharge device including a screen grid electrode, means for regenerating the succeeding tuned circuit, and an auxiliary space discharge device for regenerating the preceding tuned circuit.

Another object of the invention is to provide a portable receiver containing a tunable loop antenna connected across the input electrodes of a screen grid tube, an electron discharge tube circuit for regenerating the input circuit of the screen grid tube, and a succeeding screen grid tube detector having its input circuit tuned and regenerated.

Still other objects of the invention are to improve generally the simplicity and efficiency of portable radio receivers, and to particularly provide a portable receiver which is not only durable and reliable in operation, but economically manufactured and operated.

The novel features which I believe to be characteristic of my invention are set forth in particularity in the appended claims, the invention itself, however, as to both its organization and method of operation will best be understood by reference to the following description taken in connection with the drawing in which I have indicated diagrammatically one circuit organization whereby my invention may be carried into effect.

For further details of the invention, reference is made to the drawing, in which the single figure shows one embodiment of the invention; which figure diagrammatically shows a radio receiver circuit, especially adapted for portability, and which circuit comprises generally a loop antenna 1 having a variable tuning condenser connected across its output terminals. While the loop col-

lecting means has been conventionally shown, it is to be clearly understood that its construction may follow any arrangement well known to those skilled in the prior art, and may be arranged on 5 the receiver in such a manner that it can be readily disposed of when the receiver is being carried from one location to another. The circuit in addition, preferably comprises a pair of successive tuned circuits, both including space dis- 10 charge devices 3 and 4.

The circuit including the device, or tube, 3 functions as a stage of tuned radio frequency amplification, having the tuning condenser 2 connected between the control electrode 5 and the 15 cathode 6 of the tube. The latter, further, includes an anode 7, a screen electrode 8 disposed between the control electrode 5 and the anode 7, and a space charge electrode 9 disposed between the cathode 6 and the control electrode 5. As 20 shown, the tube 3 requires relatively little operating voltage, the space charge electrode 9 necessitating but six volts, the screen electrode having twenty-two volts impressed upon it, while the anode 7 has but 45 volts impressed upon it.

25 The tube 3 is preferably a pentode tube in order to economize the battery voltage, it being pointed out, however, that a screen grid tube without the space charge electrode 9 may also be utilized. It is desirable, however, that whatever type of 30 tube be employed in place of the pentode tube 3, such a tube require little voltage, in order to minimize the weight of batteries usually provided in a portable radio receiver.

The amplified output of tube 3 is impressed 35 upon the input circuit of the succeeding device, or tube, 4 by means of a transformer coupling M, the primary coil 10 of the latter being connected in series with the anode 7, the secondary coil 11 being connected in series between the control 40 electrode and the cathode of tube 4. A variable tuning condenser 2' is connected across the coil 11 and between the cathode and control electrode of tube 4, the usual series capacity and shunt grid leak resistance being connected in the control 45 electrode circuit of the tube in order to permit tube 4 to function as a detector. The anode circuit of tube 4 is reactively coupled to its input circuit through a coil 12, the latter being connected in series in the anode lead 13, means being 50 provided to vary the feed-back from the output to the input circuit by providing a variable coupling between coils 12 and 13, such means being conventionally designated by the arrow 14.

55 The detector tube 4 preferably employs a screen grid electrode, thus permitting regeneration control as free as possible from any sudden "snapping" into oscillation. A radio frequency choke coil 15 is provided in series in the anode lead 13 in order to by-pass radio frequency currents 60 through the radio frequency condenser 16 connected between the anode and the cathode of tube 4. The output circuit of detector tube 4 may be connected to any desired utilization means, the latter comprising one or more stages of audio frequency amplification, and/or head-phones, loud 65 speaker and the like.

The tuned input circuit, which consists of the loop antenna 1 and the tuning condenser 2, of the pentode tube 3 is regenerated by means of 70 an auxiliary space discharge device, or tube, 16. The control electrode of the latter is connected to the lead 17 between one side of the tuning condenser 2 and the control electrode 5. The cathode 75 of tube 16 is connected between the other terminal of condenser 2 and the cathode 6 of the tube

3. The tube 16 is rendered regenerative by means of the conventional tuned anode circuit arrangement comprising a variometer 18 connected in series in the anode circuit. The feed-back, as is well known, is secured through the inherent capacity between the grid and anode of tube 16, such inherent capacity 19 being shown in dotted lines.

80 A radio frequency by-pass capacity 20 is connected between the cathode and anode circuit of tube 16, while the latter is connected to a source of voltage (not shown) adapted to supply somewhat less than twenty-two volts to the anode. It will be appreciated that the tube 16 may be of a type that consumes very little power, and therefore highly economical for use in a portable radio receiver. Proper adjustment of the variometer 18 results in the desired amount of regeneration of the tuned input circuit of pentode tube 3. The tube 16, if desired, may 90 include a screen grid electrode, with suitable feed-back arrangements.

85 A shielding means 21 shown in dotted line, is provided around the tubes 3 and 4. The shielding does not include the choke coil 15, the circuits of tubes 16 or the tuned loop circuit 1, 2; the shielding means being grounded, as at G. If desired, the tuning condensers 2 and 2' can be arranged for mechanical uni-control, the latter being represented diagrammatically by the dotted 95 lines 22. The purpose of the shielding arrangement 21 is to prevent the reaction of the regenerative circuit of the tube 4 upon the tunable loop circuit 1, 2.

90 The operation of the receiver described heretofore in detail, should be obvious from such detailed description, it being necessary only to point out that by separately regenerating the input circuit of tube 3, there is secured an independency of regeneration and amplification of tube 110 3 which is not possible if the usual feed-back arrangement were employed to regenerate the input circuit of the tube. It can be shown that it is difficult or impossible, to regenerate and amplify simultaneously by means of a single tube. 115 It will therefore be appreciated that by regenerating the input circuit of tube 3 from a separate tube, independency of regeneration and amplification is secured.

120 It will, also, be seen that by providing a screen 125 grid in tube 3, which thoroughly shields the tuned circuit 1, 2 from the tuned circuit 11, 2', the total regenerative effect of the circuit is truly cascaded. That is to say, there is obtained in the output 130 circuit of the detector tube 4 the product of the two separate regenerative effects, thereby yielding more sensitivity and easier adjustments than would be the case with a single, critical regeneration, it being understood of course that the 135 regenerations employed in each of the stages are non-critical.

140 If the circuits are not well shielded, the coupling will act regeneratively on the first circuit, the phase and amount of this feed-back depending on the relative tuning of the two circuits. The tunings required for best amplification may be such as to produce too much or too little regeneration, and since both the regenerative amplification and the normal tube amplification are affected at once it is difficult, or impossible to adjust both to 145 desired values simultaneously. It is to allow this complete shielding that the auxiliary regenerating tube must be used.

150 To manipulate the present receiver, it is merely necessary to set the tuning means 22 to the desired

signal reading, and then adjust the control 18 and 14 until the desired amplification is secured, more exact tuning being attained by means of "vernier" capacities a and a_1 operable independently. It will be found that high amplification, good selectivity and fidelity characteristics are secured by means of the present arrangement, with minimum consumption of power and operating voltage requirements.

10 To indicate why cascade regeneration is superior to a single regeneration in fidelity, suppose two circuits have normally 20 ohms resistance each. If each is regenerated sufficiently to reduce the apparent resistance to 2 ohms, the 15 total regenerative amplification is 100, and the fidelity is fair. If, however, a regenerative amplification of 100 is obtained by regenerating only one circuit, its apparent resistance will be reduced to 0.2 ohms which is so low as to seriously impair 20 fidelity.

While I have indicated and described one arrangement for carrying my invention into effect, it will be apparent to one skilled in the art that my invention is by no means limited to the particular organization shown and described, but that many modifications may be made without departing from the scope of my invention as set forth in the appended claims.

What I claim is:

30 1. A radio receiver comprising a tunable loop circuit adapted to intercept transmitted signal energy, a screened grid tube provided with an output circuit and a tuned input circuit connected to the loop circuit, an electron discharge tube provided with an output circuit regeneratively coupled to its input circuit, said electron discharge tube being connected so as to act as a regenerative detector, means for tuning said last 35 named input circuit, the output circuit of the screened grid tube being coupled to the input circuit of the second tube, an independent electron discharge device having its input circuit shunted directly across the input of the screened grid tube, said independent device having a tunable 40 output circuit for regenerating the tuned input circuit of the screened grid tube whereby there is obtained in the output circuit of the second tube substantially the product of the two 45 separate regenerative effects, a utilizing means connecting circuit coupled to the output of the electron discharge tube including filter means comprising a path of low impedance for high 50 frequency energy and a path of high impedance for high frequency energy and a shielding means for shieldingly enclosing only said screened grid tube, said regenerative detector including the coupling means between the output of the screened grid tube and the input of the regenerative detector 55 and the path of low impedance for high frequency energy whereby stray energy emanating from the circuits of said regenerative detector is, in effect, localized within said shielding means and thereby substantially prevented from affecting the input circuit of the screened grid tube.

tive detector and the path of low impedance for high frequency energy.

2. In a radio receiver, a stage of radio frequency amplification comprising a screened grid tube having input and output circuits, a loop circuit for intercepting transmitted signal energy connected across said input circuit and means comprising a variable tuning device in said input circuit for tuning said loop and input circuit to the frequency of desired signal energy, 80 an electron discharge device having an input circuit and an output circuit, said input circuit thereof being linked with said output circuit of said electron discharge device to facilitate the transfer of energy from said output circuit to 85 said input circuit thereof for producing regeneration, means associated with said electron discharge device for giving thereto a detector tube characteristic whereby said electron discharge device acts as a regenerative detector, means comprising a variable tuning device in the input circuit of said electron discharge device for tuning the input circuit thereof, an additional electron discharge device having an input circuit and an output circuit, said input circuit being shunted 90 directly across the input circuit of the screened grid tube, the input circuit of said additional electron discharge device being linked with the output circuit thereof to facilitate the transfer of energy from said output circuit to 95 the input circuit thereof for producing regeneration in the tuned input circuit of the screened grid tube, said screened grid tube acting to shield the tuned input circuit thereof from the tuned input circuit of the first mentioned electron discharge device whereby there is obtained in the output circuit of the first mentioned electron discharge device substantially the product of the two separate regenerative effects, a utilization coupling means connected in the output circuit 100 of the electron discharge tube including filter means comprising a path of low impedance for high frequency energy and a path of high impedance for high frequency energy.

3. The system described in the next preceding 105 claim in combination with a shielding means for enclosing only said screened grid tube, said regenerative detector including the coupling means between the output of the screened grid tube and the input of the regenerative detector 110 and the path of low impedance for high frequency energy whereby stray energy emanating from the circuits of said regenerative detector is, in effect, localized within said shielding means and thereby substantially prevented from affecting 115 the input circuit of the screened grid tube.
